UNITED STATES PATENT OFFICE.

JACOB S. SHERMAN, OF CHICAGO, ILLINOIS, ASSIGNOR TO UNIVERSAL LAMP COMPANY, OF CHICAGO, ILLINOIS, A CORPORATION OF ILLINOIS.

DESIGN FOR A GLASS FLASK.

Application filed July 23, 1926. Serial No. 18,474. Term of patent 14 years.

To all whom it may concern:

Be it known that I, JACOB S. SHERMAN, a citizen of the United States, residing at Chicago, in the county of Cook and State of Illinois, have invented a new, original, and ornamental Design for Glass Flask, of which the following is a specification, reference being had to the accompanying drawing, forming a part thereof.

In the drawing,

Fig. 1 is an elevational view of one side, Fig. 2 is an elevational view of the other side, and

Fig. 3 is a sectional elevation at right angles to the sides shown in Figs. 1 and 2.

I claim:

The ornamental design for a glass flask substantially as shown.

JACOB S. SHERMAN.
